United States Patent Office.

NOAH DREW, OF HOWELL, MICHIGAN.

Letters Patent No. 78,440, dated June 2, 1868.

IMPROVED WASHING-MACHINE.

The Schedule referred to in these Letters Patent and making part of the same.

TO ALL WHOM IT MAY CONCERN:

Be it known that I, NOAH DREW, of Howell, in the county of Livingston, and State of Michigan, have invented certain new and useful Improvements in Washing-Machines; and I do hereby declare that the following is a full, clear, and exact description of the construction and operation of the same, reference being had to the annexed drawings, and to the letters of reference marked thereon, making a part of this specification, in which—

Figure 1 is a longitudinal vertical section.

Figure 2 is a plane view of strainer-bottom.

Figure 3 is a perspective view of spring-wire key detached.

Similar letters of reference indicate like parts in all the figures.

The washing-machine, to which the improvements herein described are represented as applied, resembles, in its general features, the machine described in the specifications embodied in my Letters Patent, dated October 30, 1866, in which a series of peculiarly-formed plunger-heads, connected to cranks, (set out at regular intervals around a crank-shaft,) operates within an inclined yielding suds-box, successively against the clothes, placed before a moulded end-board, *b*.

In the improved machine, which I am now about to describe, I fasten the suds-box to the frame, as in the ordinary way, and construct the rods *R*, which connect the plunger-heads, *p*, with the cranks, in two parts, as at *r¹* *r²*, the latter sliding within a tube, *t*, like a telescope, a spiral wire spring, *s*, being inserted within said tube, between the two section-rods, to communicate an elastic or yielding effect to the plungers, which may be aided by a rubber backing, *i*, behind the crank-bearings, and an interposed rubber plug, placed inside of the springs.

This arrangement is intended to prevent the jar or shock always felt in this kind of machine when the crank is passing the working-centre; and in connection with this, and for the additional purpose of graduating the resistance to the hand-power of the operator, I provide for lengthening or shortening the rods, by so fitting the plungers thereon that they may be slid back or forth, and secured, when properly adjusted, by a wire key, as at *a*, inserted through into the proper hole of a range of holes in the rod, or by any other convenient device.

The usual path of travel in plunger-machines is on the bottom of the suds-box, which is evidently objectionable, as the sediment is carried back by the plungers against the clothes. To remedy this, I place in the suds-box a platform, *A*, (see fig. 2,) the lower end of which is slotted, as indicated at *e*, or otherwise perforated, to permit the dirt-sediment to fall through into a chamber or space formed by means of strips of wood interposed, with which this platform or detachable raised bottom is furnished.

When the operator turns the hand-crank *C*, the plunger-heads *p* are driven by rapidly succeeding strokes against the clothes, which presses the water through them in all directions, while the twisting motion given to the stepped faces of said plungers, by the descent of the jointed rods, towards the end of the throw of the crank, turns the clothes to fresh positions for the succeeding strokes.

This operation although excellent in its effect upon the clothes, has, from the manner in which the plunger-heads were hitherto constructed, required more hand-labor than was deemed desirable, partly from the resistance of the suds-water to the rapid motion of said plungers, and partly to the fact that their bottoms were unbroken planes, which had a tendency to adhere, by vacuum-suction, at the point of largest surface-contact, during a part of the return stroke. To remedy this defect, I now make deep longitudinal grooves in the bottoms of the plunger-heads, as well as in the sides, as seen at *n*, which permits free unobstructed motion.

To connect and disconnect readily and quickly by hand the various parts in such a machine, as herein described, I have devised and use what I term a spring-wire key, to be employed either as a key proper to connect the rods with the crank, and plungers with the rods, or as a check-pin to confine any part to its place, as, for instance, the hand-crank. This key is shown at *a*, and is illustrated on an enlarged scale in fig. 3, and is constructed simply of a piece of spring-wire, (usually brass,) which is bent into an eye in the middle, the straight shanks being left diverging, as seen. These are designed to be sprung together parallel, and inserted

in holes through the parts to be connected. But when used as a check-pin, to, say, confine the crank, one shank may be inserted through the shaft, and the other (cut short) be sprung past the outside of said shank while inserting.

Having described what I deem to be new and useful improvements in this kind of machine, I will say, further, that I usually enclose the suds-box completely, so as to confine the steam from the hot suds, and prevent splashing over.

The cover No. 1 is hinged to and turns back upon No. 2, and cover No. 3 is hinged to the side-girt of the frame, the inner-cover, No. 4, being detachable. The spring-wire keys α may be fitted so loosely that any one may insert and pull them out with the thumb and finger, and yet the spring-pressure is sufficient to keep them always in place.

I disclaim the general arrangement of the plungers, rods, and cranks, in combination with the moulded end-board b , for that has already been secured to me by Letters Patent, but—

What I claim as new, and of my invention, and desire to secure by Letters Patent, is as follows:

I claim a connecting-rod, constructed in two parts, r^1 r^2 , in combination with the tube t , spiral or equivalent spring s , and adjustable plunger-heads p , substantially as and for the purpose herein described.

NOAH DREW.
